(57) **CLAIM**

The ornamental design for a multi-prong pet chew, as shown and described.

DESCRIPTION

FIG. 1 is a perspective view of a first embodiment of a multi-prong pet chew of the present invention;

FIG. 2 is a front view of the multi-prong pet chew of FIG. 1; FIG. 3 is a back view of the multi-prong pet chew of FIG. 1; FIG. 4 is a left side view of the multi-prong pet chew of FIG. 1;

FIG. 5 is a right side view of the multi-prong pet chew of FIG. 1;

FIG. 6 is a top view of the multi-prong pet chew of FIG. 1; FIG. 7 is a bottom view of the multi-prong pet chew of FIG. 1; and,

FIG. 8 is a cross-sectional view of the multi-prong pet chew of FIG. 1 taken along line 8-8 of FIG. 2.

The broken lines in the drawings illustrate portions of the multi-prong pet chew which form no part of the claimed design.
